CLAIM

The ornamental design for a ink ribbon cartridge for printing device, as shown and described.

DESCRIPTION

FIG. 1 is a top plan view of an ink ribbon cartridge for printing device showing our new design;

FIG. 2 is a front view thereof;

FIG. 3 is a rear view thereof;

FIG. 4 is a right side view thereof;

FIG. 5 is a left side view thereof,

FIG. 6 is a bottom view thereof, and,

FIG. 7 is a top perspective view thereof from one side.

Dotted lines on FIG. 6 are to show the path of the ink ribbon and are not claimed as a part of the design.

(73) Assignee: **International Imaging Materials, Inc.**, Amherst, NY (US)
